Inventor
W. Kimbrough,

By Clarence A. O'Brien,

Attorney

UNITED STATES PATENT OFFICE.

WILLIAM KIMBROUGH, OF BAKERSFIELD, CALIFORNIA.

REFLECTING SIGNAL.

Application filed February 10, 1926. Serial No. 87,336.

This invention relates to signalling devices, and is more particularly adapted to a reflecting signal which is operated by the light rays received from the headlight of approaching vehicles.

One of the important objects of the present invention is to provide a reflecting signal which may be placed in the roadway as well as adjacent the same, the signal being of such construction as to enable the wheels of motor vehicles to pass over the signal without breaking or otherwise damaging the same.

A still further object is to provide a reflecting signal of the above mentioned character which will at all times be positive and efficient in carrying out the purposes for which it is designed, means being further associated with the signal for automatically maintaining the same in an operative position even when the wheels of a motor vehicle accidentally engage the signal when passing thereover.

A still further object is to provide a reflecting signal of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawings forming a part of this application and in which like numerals designate like parts throughout the same:

Figure 1 is a side elevation of the reflecting signal embodying my invention showing the same supported in the ground.

Figure 2 is a vertical sectional view therethrough, and

Figure 3 is a fragmentary detail perspective of a modification showing the hinge construction for facilitating the swinging of the signal in either direction.

In the drawing, wherein for the purpose of illustration is shown the preferred embodiment of my invention, with reference more particular to Figures 1 and 2, the reflecting signal is designated generally by the numeral 1. The reflecting signal comprises the base 2 which is formed of a rela-

tively wide strip of sheet metal, the same having its lower end rolled as indicated at 3. This base plate is embedded vertically in the ground either in the center of the highway, or at the side thereof in such a manner as to have the upper portion of the base plate projecting above the surface of the road as indicated at 4.

The reflecting signal further includes the reflector carrying member 5 which is also formed of sheet metal material and is of substantially the same width as the base plate 2. The lower portion of the plate 5 is hingedly secured to the upper portion 4 of the base plate 2 as indicated at 6, an axial coil spring 7 being associated with the hinge for the purpose of normally maintaining the plate in vertical alignment. Suitable coacting stops 8 and 9 are formed on the plates 2 and 5 respectively adjacent their hinged ends and are arranged on opposite sides of the hinge connection between the plates as is more clearly shown in Figure 2. These stop members will limit the swinging movement of the reflector carrying member 5 in one direction and are preferably formed by providing laterally disposed projections on each of the side edges of the plate which lateral projections are bent rearwardly.

The upper portion of the plate-like member 5 is circular design and adapted to be supported on the opposed sides or faces of the circular portion of the member 5 are the reflectors 10 and 11 respectively. The reflector 10 is preferably colored red, while the reflector 11 is colored blue. These reflectors are secured in position on the opposed sides of the circular portion of the plate 5 by means of the retaining or clamping rings 12 and 13 respectively, the rings being secured in position on the opposed sides of the plate through the medium of the bolts 14. The manner in which the clamping rings 12 and 13 cooperate with the reflectors 10 and 11 is also more clearly shown in Figure 2 of the drawing.

Also secured on opposite sides or faces of the circular portion of the plate 5, and encircling the reflectors 10 and 11 are rubber protector rings 15 and 16 respectively. These rubber protector rings are of substantially the same diameter as the diameter of the circular portion of the plate and further

of a greater thickness than the greatest thickness of the reflectors so that the outer faces of the respective rubber protector rings will project beyond the thickened portion 5 of the respective reflectors.

The purpose of this arrangement will be hereinafter more fully described.

The rubber protector rings are secured on the plate 5 through the medium of the bolt 17, and suitable pockets 18 are formed in each of the rubber protector rings adjacent the perimeter for accommodating the head as well as the threaded ends and nuts carried thereon of the securing bolt so that the 10 ends of the bolts will not project beyond the outer faces of the respective protector rings. The inner opposed faces of the protector rings are also provided with pockets 19 to accommodate the bolts 14 which secure the 15 reflector retaining rings.

A reflecting signal of the character above described is arranged preferably in the roadway adjacent each side thereof so that the red colored reflectors 10 of the pair of 20 signals will be disposed adjacent or rather facing the intersection or curve in the road and should a motor vehicle approach the intersection, the blue colored reflector will receive the rays of light emanating from the 25 vehicle headlights of the approaching vehicle, and such rays of light will be utilized to display a signal to the driver of the approaching vehicle that the vehicle is about to approach an intersection or a curve. 30 The light of a vehicle approaching from the opposite direction will be cast upon the red colored reflector which is arranged on the opposite side of the road, thus warning the driver of the vehicle of the intersection 35 or curve in the road.

Should the wheels of the vehicle traveling over the highway accidentally engage the signal, the hinge 6 will permit the signal to swing downwardly in the direction of the 40 arrow so that the wheels will pass over the signal and will not come in contact with the reflectors due to the provision of the rubber protector rings and will thereby enable the vehicle to pass over the signal without breaking 45 or otherwise damaging the reflector members. After the vehicle wheels have passed over the signal, the axial coil spring 50 will again return the plate 5 to its normal upright position, the stop members 8 and 9 55 maintaining the signal member in its operative position.

In Figure 3 of the drawing, I have illustrated a modification wherein the signal member is permitted to swing in either direction and this construction is necessary where the signal member is arranged at the center of the intersection, and is liable to be struck by vehicles approaching in either direction.

In the modification, the base 20 is provided with the attaching flanges 21 and 22

which are disposed in opposite directions, the same being adapted to be secured in any suitable standard or support which is embedded in the ground, the flanges being provided with suitable openings illustrated at 70 23 to receive the appropriate fastening means. The reflector carrying member is indicated at 24, and an intermediate strip 25 is hingedly secured at its lower end to the upper portion of the base 20 as illustrated at 75 26, the upper portion of the intermediate strip 25 being hingedly secured to the lower end of the reflector carrying member 24 as at 27. These hinges are disposed on opposite sides of the intermediate strips. 80

An axial coil spring 28 is associated with each of the hinges.

Lateral projections 29 are formed on the side edges of the intermediate strips 25, adjacent the lower portion thereof, and these 85 projections are disposed rearwardly for cooperation with similar projections 30 formed on the side edges of the upper portion of the base 20. These coacting pairs of projections provide a means for limiting 90 the swinging movement of the strip 25 in one direction. A lateral projection 31 is formed on each of the side edges of the intermediate strip 25 adjacent the upper portion thereof and are disposed forwardly 95 for cooperation with the forwardly disposed projections 32 formed on the side edges of the reflector carrying member 24 adjacent the lower end thereof. The last mentioned pair of lateral projections 31 and 32 cooperate to provide a means for limiting the forward swinging movement of the intermediate strip 25, and the reflector carrying member 24.

This construction enables the signal to 100 be swung in either direction and it is of course understood that the signal member is protected by the rubber protector rings in the same manner as has been heretofore more fully explained.

It will thus be seen from the foregoing description, that I have provided a highly novel, yet simple signal which utilizes the rays of light from the headlights of approaching vehicles for actuating the signals, and furthermore a signal of the above mentioned character will at all times be positive and efficient in carrying out the purposes for which it is designed.

While I have shown the preferred embodiment of my invention it is to be understood that minor changes in the size, shape and arrangement of parts may be resorted to without departing from the spirit of the invention or the scope of the appended claims.

Having thus described the invention, what I claim as new and desire to secure by Letters Patent is:—

1. A reflecting signal comprising a base,

- a carrier member secured on said base, a reflector, a clamping ring extending over the edge portion of the reflector and secured on the face of said carrier member, and a 5 rubber protector ring secured on said face of the carrier member and extending over the clamping ring, said rubber protector ring being of greater thickness than the reflector.
- 10 2. A reflecting signal comprising a base, a carrier member hingedly secured at its lower end portion to the upper portion of the base, a reflector arranged on the face of the carrier member, an axial coil spring 15 associated with the hinge connection between the base and the carrier member, and coacting stop members extending laterally from the lower portion of the carrier member and the upper portion of the base.
- 20 3. A reflecting signal comprising a base plate extending vertically, a reflector carry-

ing member, an intermediate strip hingedly secured at its lower edge to the upper edge portion of the base plate, the upper edge portion of the intermediate strip being 25 hingedly secured to the lower edge portion of the reflector carrying member, the aforementioned hinges being disposed on opposite sides of the intermediate strip, an axial coil spring associated with each hinge, co- 30 acting stop members carried by the lower portion of the intermediate strip and the upper portion of the base plate, and additional coacting stop members extending laterally from the opposite side of the 35 upper portion of the intermediate strip and the lower portion of the reflector carrying member.

In testimony whereof I affix my signature.

WILLIAM KIMBROUGH.
